BOTTOM MARGIN GUIDE FOR TYPE-WRITING MACHINES

Helge Krogsgeng, Bronxville, N. Y., assignor to
 Krogsgeng Laboratories, Inc., New York, N. Y.,
 a corporation of New York

Application February 26, 1946, Serial No. 650,162

12 Claims. (Cl. 197—189)

1

This invention relates to a bottom margin indicator for typewriters and more particularly to such a device in which an indicating member is arranged to move proportionately to the rotary movement of the typewriter platen and, by such movement, to function in one way or another to warn the operator of the typewriter that the point has been reached where typing on a sheet of paper in the machine should be discontinued to provide a desired margin at the bottom of the sheet.

An important object of the invention is the provision of a margin indicator which may most easily be conditioned by the operator, when a sheet is inserted in the typewriter, so that, without further attention, it will function to signal the completion or approaching completion of typing within a predetermined bottom margin upon the sheet.

Another object is the provision of a margin indicator which, having once been adjusted to afford a signal for a given bottom margin on a sheet of a given length, need not be readjusted for operation with successive sheets until it is desired to have the device signal a different size bottom margin or to have it function with respect to a sheet of a different length.

Another object is the provision of a margin indicator in which a movable indicating member, at all points in its range of movement, is substantially in the same field of vision with the type-impact point of the typewriter; so that while an operator's vision is focused upon words being typed, the said movable indicating member affords a visual warning of the approaching bottom line of the typed sheet.

Another object is the provision, in a margin indicator, of a movable indicating member which, upon reaching a position correlated to a predetermined bottom marginal point of a sheet in the typewriter, automatically becomes reset at a starting position from which it may function with respect to another sheet thereafter to be typed.

Another object is the provision in a margin indicator, of an audible signal arranged to be sounded when the bottom marginal point of a sheet in the typewriter has been reached.

Another object is the provision of a bottom margin indicator which either may be built into a typewriter as an integral part thereof, or may be provided as an accessory which may be easily attached to a typewriter.

Another object is the provision of a bottom margin indicator in which at least one part thereof may replace or be combined with and perform the function of a conventional part of a typewriter, thereby avoiding undesirable duplication of parts.

The foregoing and other objects and advantages of the present invention may easily be perceived from the illustrative embodiment shown in the accompanying drawings. It should be under-

2

stood that this embodiment represents only one of numerous ways and structures in which the present invention may be practiced.

In the drawings:

Fig. 1 is a fragmentary perspective view of a typewriter showing the platen thereof and portions adjacent said platen, with a bottom margin indicator, according to the present invention, associated therewith, certain parts being broken away to show the mechanism more clearly;

Fig. 2 is a vertical section substantially on the line 2—2 of Fig. 1, showing a movable indicating member carried upon a bail on the typewriter in condition to move in response to turning of the platen to advance a sheet of paper through the machine;

Fig. 3 is a front elevational view of the bail, partly cut away to show the said indicating member, in vertical section, in the position and condition which it assumes momentarily at the instant when a bottom margin signal should be given;

Fig. 4 is a cross-sectional view on the lines 4—4 of Figs. 2 and 3;

Fig. 5 is a fragmentary perspective view of the movable indicating member and certain related parts;

Fig. 6 is a view, in the same perspective as Fig. 5, of certain portions of the movable indicating member, including a latch which forms a part of said member;

Fig. 7 is a view, in the same perspective as Figs. 5 and 6, of the said latch and a plunger which, also, forms a part of the movable indicating member; and

Fig. 8 is a fragmentary top plan view of one end of the bail, showing, partly in full lines and partly in broken lines, a rod or tongue which functions to operate the mentioned audible signal.

The present invention, in its entirety, may best be understood from Fig. 1, wherein most of the essential elements and some optional parts of the invention are shown as attached to or incorporated into a typewriter.

The platen 11 of the typewriter is constrained to turn with a spindle 12 which extends outwardly from one end of the said platen, through a suitable aperture or bearing in a carriage plate 13. The spindle 12 or a similar spindle (not shown) similarly extends outwardly from the opposite end of the platen 11 through an aperture or bearing in a carriage plate 14. Thus, the mentioned carriage plates support the platen 11 for rotation and carry it axially from right to left under spring tension, in a well understood manner, as characters are being typed upon a paper sheet positioned upon the said platen.

A handwheel 15 may be fixed upon the spindle 12 at one end of the platen 11 to facilitate rotation of the latter; and a hand lever 16 may be

provided adjacent the other end of the platen, and operatively related to the latter in a well-known manner (not shown), to afford means for rotating the platen, after one line of typing has been completed, and for manually moving the platen toward the right, in preparation for the typing of another line. All the foregoing is believed to be well understood by those conversant with typewriters as thus far developed.

The present invention preferably comprises an indicating member 17, arranged to move longitudinally with respect to a bail 18; a threaded shaft 19 (Figs. 2, 3, 4, and 5) for imparting such movement to said indicating member in response to rotation of said shaft through a gear train 20 which is driven by the spindle 12; and a trip member 21 which coacts with the indicating member at the proper time, to signal that typing should be discontinued, on the sheet then in the typewriter, to provide the desired bottom margin thereon. The invention also may comprise a bell 22 to function as an audible signal.

The gear train 20 may be substantially inclosed within a cover partially shown at 23 and partially omitted from the drawing to show the gear train more clearly. The said gear train, or its mechanical equivalent, may be of any design suitable for causing the shaft 19 to rotate with the spindle 12. It is shown in the drawings as comprising a primary gear wheel 24 fixed upon and constrained to rotate with the spindle 12, and having peripheral teeth meshing with an inner toothed portion of a reducing gear wheel 25 having peripheral teeth which, when the bail 18 is in its operative position as shown in full lines in Fig. 1, are in mesh with a pinion 26 fixed upon the near end of the shaft 19, to drive the latter and thus move the indicating member 17.

The ball 18 is carried upon arms 27, 28, which, respectively, are pivoted to the plates 13, 14 at pivot points 29, 30. As the ball 18 must be pivotally raised to its inoperative position, as shown in broken lines in Fig. 1, to insert the leading edge of each new sheet of paper thereunder, the gear cover 23 is left open as at 23a, to permit such pivotal movement of the bail and more particularly to permit the pinion 26 to pass into or out of the cover 23 when the bail is so moved.

A bail similar to bail 18 is commonly provided on typewriters, and the present invention utilizes the bail as a supporting means for certain important elements of the invention. As best understood from Fig. 2, the bail 18 is in the form of a tube, to one end of which its supporting arm 28 is fixed by a machine screw 31 which passes through a suitable hole in said arm and is threaded into a plug 32 which may be friction-fitted tightly into the end of the bail. The supporting arm 27 for the other end of the bail 18 may be fixed to the latter by means of a plug 33, tightly friction-fitted into the end of the bail and also into a suitable hole in the arm 27. The plug 33 and the arm 27, preferably, are fixed to the bail only after the shaft 19 and related parts are assembled within and on the bail.

The shaft 19 is rotatably supported at one end, within a suitable axial bore 34 in the inner end of the plug 32. At its other end the shaft 19 is shouldered as at 35 to form a slightly reduced end portion 36. The shoulder 35 abuts the plug 33, thereby causing the shaft 19 to be held against material axial movement within the bail, and the reduced end portion 36 extends outwardly and rotatably through a suitable bearing aperture in the plug 33. The end portion 36 extends out-

wardly beyond the plug 33 to receive the pinion 26 which is tightly fixed thereon in any suitable manner as by a tight friction fit, or a key, or by coacting flats on the end portion 36 of the shaft and on the interior of the pinion, such flats being indicated at 37 in the drawing. Thus, the shaft 19 is constrained to turn with the pinion 26. The latter may be held upon the shaft 19 by any suitable means, as, for example by a nut 38.

10 The following description of the indicating member 17 should be more easily understood if it is observed that at the initial insertion of the sheet in a typewriter, the member 17 will be positioned as shown in Fig. 2 and may be manually conditioned to coact with the threaded shaft 19 so that as the platen 11 is turned to advance the sheet, line by line through the machine, the shaft 19, through the medium of its threaded portion 19a, will coact with a correspondingly threaded portion of the indicating member 17 to move the latter toward the right, until the desired bottom line of typing is reached. At that time the member 17 will have reached the trip member 21 which will free the interengaging threaded portions of the shaft 19 and the member 17, thereby permitting the latter to be pulled back to its initial position by a spring 39.

The assembly, hereinbefore characterized as the movable indicating member 17, comprises a sleeve 40 which extends in a close non-binding fit, about the threaded portion 19a of the shaft 19. Upon the top of the sleeve 40 is mounted a block 41, which as best seen in Figs. 2-4, extends through an elongate slot 18a in the bail and has wings 42 formed thereon, extending outwardly and downwardly about the exterior of the bail. A slight sliding clearance is provided between the block 41 and the slot 18a and the exterior surface of the bail.

40 A cap 43 overlies the block 41; and the sleeve 40, the block 41, and the cap 43 are rigidly fastened together by small screw bolts 44, 45, having nuts 46, 47 upon their outer ends. The bolts 44, 45 have flared flat heads which are seated within slots 40a, 40b in the top of the sleeve 40. The said slots facilitate assembly of the device, slots 40a having an open-end and slot 40b having an enlarged portion 40c, to permit the insertion of the said bolts in the mentioned slots.

50 The indicating member 17 also includes a plunger 48 which extends vertically through suitable openings in the cap 43, the block 41, and the sleeve 40, and has a preferably partial-cylindrical concave surface 49 at its lower end which is grooved or threaded to enable it to mesh with the threaded portion 19a of the shaft 19, as may best be understood from Fig. 3. The plunger 48 is urged upwardly by a compression coil spring 50, which extends around the upper end of said plunger and is interposed between the cap 43 and a button or head 51 fixed upon or integral with the upper end of the plunger 48.

A U-shaped latch 52 serves to limit the upward movement of the plunger 48 and also to hold the latter in its lowermost position. The latch 52, best visualized in its entirety in Figs. 6 and 7, has one arm 53, which is hereinafter sometimes referred to as a latch-arm, a second arm 54, which is hereinafter sometimes referred to as a trip-arm, and a base portion 55. The latch 52 is urged toward the right by a short, compression, coil-spring 56 which is interposed between the block 41 and the trip-arm 54, being held in that position by a short stud 57 which is fixed into the arm 54 and extends axially within sev-

eral coils of the said spring. The stud 57, however, is short enough to avoid interfering with the intended limits of movement of the latch 52.

The block 41 is suitably recessed or slotted, longitudinally, to receive the base portion 55 of the latch slidably therein as may best be understood from Fig. 6; and the block 41, also, is recessed or slotted transversely, as best seen at 58 in Figs. 2 and 6. The slot 58 extends alongside of and in direct communication with the vertical aperture, in the block 41, through which the plunger 48 extends, and the latch arm 53 may slide transversely (longitudinally of the indicating member 17) between a leftward position of the latch in which the latch arm 53 seats within a shallow lateral rabbet 59 in the plunger 48, as shown in Fig. 3, to limit the upward movement of said plunger, and a rightward position of the latch in which the latch arm 53 seats within a deeper lateral rabbet or groove 60 in the plunger 48, immediately adjacent and communicating with the rabbet 59, to hold the plunger 48 in its lowermost position, as shown in Fig. 2.

It may be understood that, if the plunger 48 is in its uppermost position, as shown in Fig. 3, and is manually pressed downwardly to its lowermost position upon the initial insertion of a sheet in the machine, the downward movement of the plunger brings the groove 60 into horizontal register with the latch-arm 53 whereupon the latter automatically moves toward the right into the groove 60 in response to the force of the spring 56, whereby the plunger is held in its lowermost position, as shown in Fig. 2, with its lower end in mesh with the threaded portion 19a of the shaft 19. In this condition, the indicating member 17 threads its way along the threaded portion 19a of the shaft 19, as the latter turns in response to rotation of the platen 11 to advance the sheet through the machine.

If, then, the latch 52 is moved to the left within the transverse recess 58 when the desired bottom line of typing has been reached or completed, the plunger 48 becomes free to move back to its uppermost position in response to the force of the spring 56 and the indicating member 17 becomes freed of coaction with the threaded portion 19a, and is instantly pulled back to its initial position by the spring 39. In the present invention, the last mentioned movement of the latch 52 is accomplished automatically, when the last desired typing line on a sheet is reached or completed, by means hereinafter described.

The movable indicating member 17 is shown in Fig. 2 in its initial position corresponding to the initial position of a sheet of paper in the typewriter. The member 17 is yieldably held in that position by the coil-spring 39 which extends about the shaft 19, suitably anchored at its opposite ends to the plug 32 and the sleeve 40. These anchorages, for example, may be similar, and may be effected by having several end coils of the spring 39 extend tightly about reduced extensions 61 and 62, provided respectively on the opposed ends of the plug 32 and the sleeve 40 as best illustrated in Fig. 2. Although not shown in the drawing, the anchorage of the end coils of the spring 39 and the extensions 61 and 62 may be made more secure either by providing, on those extensions, threads or grooves into which the said end coils of the spring 39 may seat, or the said coils may be spot-soldered to said extensions. Anchorage means, other than those just described, may be employed as desired.

When the indicating member 17 is in its initial

position as shown in Fig. 2, the spring 39 is in its free or unloaded condition. The characteristics of the spring 39 are such that in the operation of the device, the said spring does not acquire a set which could either elongate or shorten the normal length of the spring, therefore the initial position of the indicating member 17 is always as shown in Fig. 2.

The trip member 21 is provided as a means which, when the desired bottom line of typing has been completed, serves to move the U-shaped latch 52 toward the left relatively to the block 41 within which it is mounted. Actually, in operation the trip member 21 serves to arrest the rightward movement of the latch 52 by engaging the trip arm 54 of the latch, as the indicating member 17 threads its way toward the right along the screw portion 19a of the shaft 19 in response to rotation of said shaft as the platen 11 is turned to advance a sheet through the machine, the remainder of the indicating member, meanwhile, continuing to move rightwardly to an extent sufficient to cause the latch-arm 53 to move out of the groove 60 in the plunger 48. This permits the plunger 48 to rise and become disengaged from the threaded portion 19a of the shaft 19 so that the indicating member may be pulled back to its initial position by the spring 39 in readiness to function with respect to the next sheet to be inserted in the machine.

The trip member 21, as shown in Figs. 2 and 3, may comprise an interior friction plate 61 which is somewhat wider than the slot 18a and disposed in sliding contact with the interior surface of the bail 18, a stem 62 integral with or fixed to said plate and extending upwardly through said slot, a head 63 integral with or fixed upon the upper end of the stem 62, an exterior friction plate 64, somewhat wider than the slot 18a and loosely disposed upon the stem 62 in sliding contact with the exterior surface of the bail 18, and a compression coil-spring 65, mounted about the stem 62 between the head 63 and the plate 64. The arrangement is such that the bail is yieldably gripped between the plates 61 and 64, and the trip member 21 may be slid manually along the slot 18a of the bail to a position at which it may coact with the latch 52 to cause the automatic return of the indicating member 17 when the last desired line of typing has been reached or completed.

The bail 18 may be provided with markings 66, and the exterior plate 64 of the trip member 21 may be formed with a pointer 67 to aid an operator in achieving accuracy of positioning of the said trip member to cause the latter to coact with the indicating member 17 to signal, at the desired time, the approach to or completion of the desired last line of typing.

Obviously, an operator will quickly learn the proper setting of the trip member to signal a desired margin on a sheet of a certain length. For example, the operator may learn that, if the pointer 67 is set at the marking bearing the number 5, the signal will occur upon reaching a point about two inches from the bottom of a sheet which is 11 inches in length or that for a sheet of the same length, the pointer 67 may be set at numbers 10 or 15, respectively, to signal bottom margins of 1½ inches or 1 inch. If a sheet 13 inches long is being used the operator may learn that pointer settings at 10, or 15, or 20, may correspond substantially to bottom margins of 2 inches, 1½ inches, or 1 inch. After a short period of usage the operator will know at what

position to set the trip member 21 to cause a signal approximately at any desired distance from the bottom of a sheet of any size commonly used.

No attempt has been made in the drawings to indicate precise gear and thread ratios. Obviously, such ratios can be arrived at by simple computations to assure satisfactory movement of the indicating member 17.

Although the automatic leftward movement of the indicating member 17, at the desired predetermined last line of typing, may serve as an adequate signal, and for that reason, the invention, as thus far detailed may be considered completely operative, nevertheless, it may be preferred to have a clearly audible signal. Therefore, I illustrate a bell and a bell operating arrangement which may advantageously be employed.

The bell or gong 22 may be fixed in any suitable manner as by a bracket 23 fastened to the rear of a paper support 28 which travels with the platen 11. A lever 70 having a clapper 71 on one end thereof, adjacent the bell 22, may be pivoted to the bail arm 28 at 72 to turn substantially horizontally about a vertical axis, and the other end of the lever 70 may have a vertical extension 73, extending downwardly through a short slot 74 in the top of the bail 18, thence into an aperture 75a in one end 75 of a preferably flat rod 16 which extends within the bail 18, in a position overlying the spring 39, and has an offset 77 at its other end, extending outwardly through the slot 18a terminating in an impact head 78 which is adapted to be struck momentarily by the block 41 of the indicating member 17 when the latter is pulled sharply to the left by the spring 39 at the desired signal time.

The main or central portion of the rod 16 may be longitudinally ridged or may be curved laterally somewhat to enhance its strength. The end 75 of this rod works within a chordal space 79 provided by a flat 80 formed on the top of the plug 32 and wings 78a (Figs. 5 and 8) on the impact head 78, support the other end of the rod 16.

The mentioned impact of the block 41 upon 45 the head 78 causes the lever 70 to rotate clockwise, as viewed in Fig. 1, bringing the clapper 71 into sharp impact with the bell 22 to ring the latter. This impact is only momentary because the lever 70 is normally held, with its clapper 71, 50 out of contact with the bell, by a small, tension coil-spring 81, connected, at its ends, to the bail arm 28 and the lever 70.

In order to strike the rod 16 to sound the bell, the indicating member 17 moves leftwardly, beyond its initial position shown in Fig. 2, as a result of its inertia, gained in its spring-impelled leftward movement at the desired signal time. This leftward movement causes a momentary compression of the spring 39 which causes the 60 indicating member 17 to return to its initial position immediately upon sounding the bell.

Although the foregoing description should give an understanding of the operation of the invention, it may be made clearer by the following recital of a complete cycle of operation which stresses the sequence rather than the details of operation.

Let it be assumed that the operator, intending to type on a sheet, 11 inches in length, knows 70 that a desired margin will be signaled if the trip member 21 is set at number 5 on the bail markings 56. He so sets the trip member; then inserts the sheet into the machine, turning the handwheel 15 for this purpose. He then lifts the 75

bail 18, passes the leading edge of the sheet thereunder, and then lowers the bail. Then he aligns the sheet by seeing that its upper edge is just barely visible above the bail and is substantially parallel thereto. Without regard to the present invention, this procedure is customary in the use of any typewriter having a bail.

The operator, then, merely presses the plunger 48 down (it having theretofore been in its uppermost position) and the latch 52 holds it down in meshing engagement with the threaded portion 19a of the shaft 19. Then the platen 11 is turned to advance the sheet to a starting point of typing and to move the sheet line for line, through the machine. The turning of the platen 11 causes proportionate turning of the shaft 19 and rightward movement of the indicating member 17.

When the paper has advanced through the typewriter to a point just before the last desired line of typing, the latch arm 54 of the latch 52 engages the trip member 21, thereby preventing further rightward movement of the latch 52. Upon further rotation of the platen 11 to bring the sheet into position for the last line of typing or to carry the sheet beyond that position, the remainder of the indicating member 17 moves further to the right causing the latch 52 to release the plunger 48 to bring the latter and other parts to their positions shown in Fig. 3, particularly to unmesh the said plunger and the threaded portion 19a of the shaft 19.

In this condition the indicating member 17 is pulled sharply to the left; its inertia causes it to strike the rod 16 to sound the bell, and then the spring 39 assumes its unloaded condition with the indicating member 17 in its initial position in readiness to function with respect to the next sheet inserted in the typewriter. As long as the operator continues to use the same size sheets and desires the same bottom margin, the trip member 21 need not be readjusted. The trip member need only be readjusted when a different size sheet is to be used or a different size bottom margin is desired.

The present invention permits turning the platen forward to effect a correction and, then, turning it back to resume typing. In this, however, the operator will exercise a little care to assure that whenever the platen is being turned in either direction, the bail will be in its normal position with the pinion 26 in mesh with the gear wheel 25, as otherwise the necessary relationship between the movements of the platen and the indicating member would be destroyed. This requirement of the operator, however, is not a drawback for it is a matter of habit for the operator to put the bail in its normal position before turning the platen or operating any other part of the typewriter.

In order to safeguard against possible jamming of any parts if an operator were inadvertently to rotate the platen 11 backwardly to an excessive extent, the shaft 19 is provided with an unthreaded reduced portion 19b (Fig. 2) which limits the extent to which the indicating member 17 may thread itself along the shaft 19 in a leftward direction. This limit of movement avoids any jamming of the said indicating member.

It should be apparent that the invention as described herein is simple, effective both visually and audibly, easy of operation, useful either as an accessory or as a built-in part of a typewriter, and, generally, yields all the various objects and advantages hereinbefore ascribed thereto. Also,

it should be obvious that the device, particularly the gear and threaded shaft portions thereof, may be designed for any given diameter of platen and that various other structural embodiments and modifications may be employed without departing from the invention as defined in the following claims.

What I claim is:

1. A bottom margin indicator for a typewriter having a horizontally disposed platen for supporting a sheet and for moving it through the typewriter; the said indicator comprising an indicating member supported for movement along a linear course; a screw, coacting with said platen and said indicating member for moving the latter along said course in direct proportion to the movement of the sheet through the typewriter; means independent of said sheet for interconnecting said screw and said member, to condition the latter for movement in one direction along said course in response to advancing movement of the sheet through the typewriter; means independent of said sheet for automatically disconnecting said member and said screw upon such advancement of the sheet to a predetermined extent through the typewriter; and means, operative upon such disconnection, for moving said member in the opposite direction.

2. A bottom margin indicator for a typewriter having a horizontally disposed platen for supporting a sheet and for moving it through the typewriter; the said indicator comprising a rotatable, threaded shaft; means for rotating said shaft in direct proportion to the movement of the sheet through the typewriter; an indicating member, adapted to coact with a threaded portion of said shaft, whereby to be moved proportionately to such movement of the sheet; manually operable means independent of said sheet for establishing such coaction; and means, independent of said sheet and operative upon said indicating member reaching a predetermined position in its mentioned movement, for automatically disestablishing such coaction.

3. A bottom margin indicator for a typewriter having a rotatable cylindrical platen for advancing a sheet through the typewriter and a bail adjacent to and parallel to said platen and adapted to engage such a sheet to maintain the latter in intimate association with said platen; the said indicator comprising an indicating member, supported upon and movable along said bail; normally non-operative transmission means adapted for change to operative condition to establish a transmission connection between said platen and said indicating member to impart such movement to the latter in direct proportion to rotative movement of said platen; means for automatically disestablishing such a connection in response to movement of said indicating member to a predetermined extent following the establishment of such a connection; and means, operative automatically upon such disestablishment of such connection, for signaling the completion of the predetermined movement of the indicating member.

4. A bottom margin indicator for a typewriter having a rotatable cylindrical platen for supporting and advancing a sheet through the typewriter and a bail adjacent to and parallel to said platen; the said indicator comprising a threaded shaft having common support with said bail; actuating means for rotating said shaft in direct proportion to the rotation of the platen; an indicating member coacting with said bail for re-

straining said indicating member against rotation relatively to the axis of said shaft and having a shaft-engaging portion which is releasably engageable with respect to a threaded portion of said shaft; manually operable means for interengaging said threaded portion of said shaft and said shaft-engaging portion of the indicating member to cause movement of the latter in one direction; a trip member adjustable to any one of various positions in the path of movement of said indicating member and adapted to coact with the latter to release said shaft-engaging portion of the indicating member from engagement with said threaded portion of said shaft; means, operative upon such release, for moving the said indicating member automatically in the opposite direction; and signal means operative in response to the latter movement.

5. A bottom margin indicator for a typewriter having a horizontally disposed, rotatable, cylindrical platen for supporting a sheet and for advancing it through the typewriter; the said indicator comprising a tubular bail member extending adjacent and parallel to said platen and having a substantially straight longitudinally extending slot therein; a threaded shaft rotatably supported within said bail member; an indicating member supported upon and adapted to move along said bail member and having a portion extending through said slot and coacting with the walls of the bail member defining said slot for restraining said indicating member against rotation; means for rotating said shaft in direct proportion to rotation of said platen; non-rotatable means coacting with and operatively interconnecting said indicating member and a threaded portion of said shaft whereby to thread said indicating member in one direction along said shaft when the latter is rotated; automatic means for breaking such interconnection at a predetermined point in the mentioned movement of the indicating member along said shaft; and means operative upon the breaking of such interconnection for moving said member in the opposite direction.

6. A bottom margin indicator for a typewriter having sheet-actuating means for moving a sheet therethrough; the said indicator comprising a threaded shaft; means for rotating said shaft in direct proportion to such movement of the sheet; an indicating member supported for rectilinear movement along said shaft; yieldable means for holding said indicating member normally in a first position; means independent of said sheet for intermeshing said shaft and a portion of said indicating member to render the latter movable along said shaft to a second position in response to rotation of the latter; and means operative upon said indicating member reaching said second position for automatically unmeshing said shaft and said indicating member to render the latter movable from such a second position to said first position.

7. A bottom margin indicator for a typewriter having sheet actuating means for moving a sheet therethrough; the said indicator comprising a threaded shaft; means for rotating said shaft in opposite directions in direct proportion to such movement of the sheet in opposite directions; an indicating member guided for movement along a course adjacent to and parallel to said shaft; a spring fixed to and normally holding said indicating member in a first position on said course; a connecting element which is carried by said indicating member and is manually movable from

an inactive position, clear of said shaft, into intermeshing engagement with a threaded portion of the latter to render the indicating member movable, against the force of said spring, from said first position to a second position upon rotation of said shaft; and tripping means adapted to coact with said indicating member at a predetermined second position of said indicating member to break such meshing engagement, thereby permitting the said indicating member to return to its said first position in response to the force of said spring.

8. A bottom margin indicator for a typewriter according to claim 7, further characterized in having an audible signal element, and means operative in response to such return movement of said indicating member, for sounding said signal element.

9. A bottom margin indicator for a typewriter having sheet actuating means for moving a sheet therethrough; the said indicator comprising a threaded shaft; means for rotating said shaft in opposite directions in direct proportion to such movement of the sheet in opposite directions; an indicating member guided for movement along a course adjacent to and parallel to said shaft in view of an operator; a spring fixed to and normally holding said indicating member in a first position on said course; a connecting element which is associated with said indicating member and is manually movable from an inactive position, clear of said shaft, into intermeshing position, in meshing engagement with the latter to render the indicating member movable, against the force of said spring, from said first position to a second position; and tripping means adapted to coact with said indicating member at a predetermined second position to break such meshing engagement, thereby permitting the said indicating member to move back to its said first position; further characterized in that the said shaft has an unthreaded portion of reduced diameter to limit the coaction of said shaft and indicating member for moving the latter in a direction, from said first position, opposite to movement to such a second position.

10. A bottom margin indicator for a typewriter having a horizontally disposed rotatable cylindrical platen for supporting a sheet and for moving it through the typewriter, and a tubular bail disposed in front of and parallel to said platen; said indicator comprising a rotatable threaded shaft within said bail; motion-transmitting means between said platen and shaft for rotating the latter proportionately to rotation of said platen; an indicating member, mounted upon said bail for movement longitudinally of the latter along a slot provided in said bail and having an element extending through said slot and being manually movable into meshing engagement with said shaft to condition the said indicating member for movement along the shaft, from a first to a second position, in response to rotation of said shaft, and also having means normally urging said element from such meshing engagement, and a releasable latch for holding said element in such meshing engagement; spring means coacting with said indicating member to hold the latter yieldably in such first position; a tripping member disposable at any one of plural predetermined positions along the mentioned slot in the bail, in the path of movement of said indicating member, and adapted to coact with said latch to release the latter at a predetermined second position of said indicating member to permit termination of

such meshing engagement; and an audible signal having operating means disposed in position for actuation by said indicating member upon movement of the latter, impelled by said spring means, from said second position, to and beyond said first position; the said spring means, also, being adapted to cushion the termination of such impelled movement of the indicating member.

11. In a bottom margin indicator for a typewriter having a longitudinally slotted tubular bail and a threaded shaft therein, rotatable in direct proportion to movement of a sheet in either of opposite directions through the typewriter; an indicating member having guide portions, in close sliding relation to portions of said bail adjacent to said slot, for guiding the said indicating member for longitudinal movement along the bail while preventing material movement of said member laterally and angularly; a shaft-engaging element having a foot adapted to intermesh with a threaded portion of said shaft, and means for yieldably holding the said element clear of such intermeshing with said shaft, said shaft-engaging element being movable manually to bring said foot into such intermeshing position; and a latch having a portion adapted to engage a portion of said shaft-engaging element to hold the latter in said intermeshing position; the said latch being adapted for disengagement from said shaft-engaging element whereby to release the latter from its said intermeshing position.

12. In a bottom margin indicator for a typewriter having a tubular bail with a longitudinal slot and a threaded shaft in said bail, which shaft is rotatable proportionately to opposite movements of a sheet in the typewriter; a movable indicating member having a shaft-guided portion and a bail-guided portion extending within said slot, which portions respectively coact with said shaft and the said slot to restrict the said indicating member against any material movement excepting movement longitudinally of the bail; a manually depressible plunger associated with said indicating member and having a foot adapted to intermesh with said shaft; spring means normally holding said plunger against such intermeshing; a latch carried by said indicating member and capable of limited movement relatively to said plunger; and a spring normally urging said latch into latching engagement with said plunger to hold the latter in its mentioned intermeshing position; the said latch having a portion at the exterior of the said indicating member for actuation of said latch to release it from latching engagement with the said plunger.

HELGE KROGSENG.
